UNITED STATES PATENT OFFICE.

JOHN JACOBSEN, OF LETHBRIDGE, CANADA, ASSIGNOR OF ONE-HALF TO
GUSTAF A. NORDQUIST, OF GREATFALLS, MONTANA.

MINER'S LAMP.

SPECIFICATION forming part of Letters Patent No. 718,128, dated January 13, 1903.

Application filed November 25, 1901. Serial No. 83,563. (No model.)

To all whom it may concern:

Be it known that I, JOHN JACOBSEN, a subject of the King of Denmark, residing at Lethbridge, in the southern district of Alberta, Canada, have invented certain new and useful Improvements in Miners' Lamps; and I do declare the following to be a full, clear, and exact description of the invention, such as will enable others skilled in the art to which it applies to make and use the same, reference being had to the accompanying drawings, and to the figures of reference marked thereon, which form a part of this specification.

My invention relates to improvements in lamps of the class used by miners who secure a lamp to their cap, from whence it spreads light upon their underground work in mines; and the objects of the invention are to provide means by which the lamp may be secured to the cap in a balanced suspended manner, so that it will preserve its plumb position whether the miner stands erect or stoops more or less down and to make such lamp easily removable from the cap and adapted to hang on a hook or peg. These objects I attain by the novel construction and arrangement of parts illustrated in the accompanying drawings, in which—

Figure 1 is a side view of a lamp suspended with my device from the cap of a human figure representing a miner. Fig. 2 shows a sheet-metal blank from which the lamp-holder is formed. Fig. 3 is a modification showing Fig. 2 made out of wire.

Referring to the drawings by reference-numerals, 4 designates the head of a miner, on which 5 is the usual miner's cap with a considerably large vizor 6, to which and to the cap is secured at 7 by stitches or other suitable means the bracket or lamp-holder 8, which is provided in its two cheek-pieces 9 with notches 10, in which the trunnions 11, provided at both sides of the upper part of the lamp 12, rest and permit the lamp to swing back and forth between the cheek-pieces. At each side of the bracket is pivoted and friction-held on a pivot 13 a hook 14, which takes above each trunnion 11, and thus keeps it in

place until it is desired to remove the lamp. Then the hook may be swung away into the position shown in dotted line 15.

16 is the wick, and 17 is the cover of the lamp, while 18 is a hook by which to hold and suspend the lamp when not in the bracket 8. When the lamp swings much backward with its top end, the hook 18 passes into the clearing 19 (see Fig. 2,) or between the upper parts of the wire at 20 in Fig. 3, if the bracket is made of wire as illustrated in said Fig. 3, that it may be; and when it is made of wire the hooks 14 may be omitted, as the trunnions are then kept in their journals by the narrow points 21 of the gaps 10, which are sprung wider only while the trunnions are forced up or down through them.

In the ordinary miner's lamp heretofore used a hook similar to hook 18 is rigidly secured to the cap, so that the lamp tilts with the stooping of the miner, and thus causes the oil sometimes to press forward to the flame and at other times to recede from it with an undesirable variation in the light. Besides that such lamps are usually secured so close to the cap that the vizor throws too much shadow on the work near in front of the miner, all of which difficulties my device aims to overcome and remedy.

Having thus described my invention, what I claim, and desire to secure by Letters Patent, is—

1. In a miner's lamp, the combination with a plate or bracket having an upper rearwardly-curved top securable to the cap and a forwardly-curved bottom end securable upon the vizor of the cap, and intermediate its ends forwardly-projecting cheek-plates having downwardly and forwardly slanting notches, of a lamp having side trunnions adapted to rest in said notches; and the friction-held hooks 14 closing the notches to prevent accidental displacement of the trunnions.

2. In a miner's lamp, the combination with a plate or bracket having an upper rearwardly-curved top securable to the cap and a forwardly-curved bottom end securable upon the vizor of the cap, and intermediate its ends

forwardly-projecting cheek-plates having downwardly and forwardly slanting notches, of a lamp having side trunnions adapted to rest in said notches; and the friction-held 5 hooks 14 closing the notches to prevent accidental displacement of the trunnions; and the combined hook and handle 18, fixed to the rear of the upper part of the lamp and projecting above the same, and a clearing for

said hook in the bracket, substantially as and to for the purpose set forth.

In testimony whereof I affix my signature in presence of two witnesses.

JOHN JACOBSEN.
